UNITED STATES PATENT OFFICE.

TAINE G. McDUGAL, OF FLINT, MICHIGAN, ASSIGNOR TO CHAMPION IGNITION COMPANY, OF FLINT, MICHIGAN, A CORPORATION OF MICHIGAN.

BURNING CERAMIC WARES.

1,416,727.

Specification of Letters Patent. Patented May 23, 1922.

Original application filed October 10, 1919, Serial No. 329,705. Divided and this application filed July 28, 1921. Serial No. 488,135.

To all whom it may concern:

Be it known that I, TAINE G. McDUGAL, a citizen of the United States, and a resident of the city of Flint, county of Genesee, and 5 State of Michigan, have invented certain new and useful Improvements in Burning Ceramic Wares, of which the following is a full, clear, concise, and exact description, such as will enable others skilled in the art 10 to which the invention relates to make and use the same, reference being made therein to the accompanying drawings, which form a part of this specification.

This application is a division of my 15 United States application Serial No. 329,705, filed October 10, 1919, to which reference is made for a more complete understanding of the invention.

For the purpose of eliminating the difficulties inherent to the use of periodic kilns, a continuous process has been developed heretofore which provides for the placing of the saggers or fire-clay slabs upon a refractory car-top and passing the cars through 25 a tunnel from three hundred feet to six hundred feet long, comprising a pre-heating, a high-temperature, and a cooling zone. With this method the saggers or slabs which support the ware are piled in mass four to eight 30 feet high on the cars, which travel the length of the tunnel-kiln in not less than twenty-four hours. This method of mass-burning, while it eliminates the necessity of workmen entering the kiln for loading and unloading purposes, and while it reduces the 35 time of firing somewhat, is nevertheless subject to the loss incident to overfiring and under-firing growing out of the uneven distribution of heat, especially from top to bottom of the mass, and to the expense of forming and handling the saggers.

A leading object of the present invention is to provide for both a more rapid and a more uniform burning of the ware than has 45 been attained heretofore, whereby the quality of the goods is improved and the percentage loss incident to even the most approved prior practice is substantially avoided. To this end I burn the ceramic wares 50 or silicate bodies while exposed openly, preferably in a single tier only, to the intense heat of a substantially flameless combustion of pre-mixed air and fuel directed against

the closely adjacent top or dome of the kiln and reflected thereby down onto the ware. 55 In this manner the individual articles are each subjected to the direct intense heat of say 2300° F. or thereabouts to 2650° F. or possibly higher as distinguished from the previous practice of piling in mass either 60 with or without saggers; and the time necessary for firing is reduced from twenty-four hours or more in the case of spark plug porcelains to as low as six hours or even less, and a more uniform grade of product is secured. 65

A further important object is to enable the heating and cooling steps to be effected at an increased rate as compared with that necessitated by the use of cars on which 70 both the wares and a large mass of refractories are necessarily carried. While this may be accomplished in various ways, I prefer to form the ware-supports as thin slabs or trays of highly refractory material which 75 themselves ride on suitable conveyor-elements of heat insulating material, the necessary body or backing of fire brick and insulating brick (heretofore carried on the cars) being stationary. In this manner the very 80 large quantity of heat necessarily wasted in the cooling of the large moving mass of the kiln as heretofore constructed is saved, and the time element incident to heating up and cooling down is greatly reduced. 85

As stated heretofore, the present invention differs from prior practices in that mass-firing is avoided, and for this purpose the wares are placed on the movable trays or other carriers in a single open tier or so arranged as to be directly subjected to the downward radiation or reflection of heat from the over-lying arch wall of the tunnel, this wall being in turn intensely heated by blasts from burners wherein air and gas 95 fuel or air and oil are pre-mixed in the proper proportion to produce substantially flameless or surface combustion, that is, wherein there is substantially no excess of either air or fuel, or wherein a small excess 100 of oxygen is admitted for the purpose of burning out organic matter contained in the raw porcelain. The articles, for example, spark plug porcelains, are thus subjected directly to the intense heat and vitrify substantially uniformly without the loss inci- 105

dent to the previous continuous kiln practice and without the depositing or formation thereon of spots due to unburned fuel.

Figure 1 is a transverse cross section of a kiln of the continuous type showing a preferred embodiment of the invention.

As more fully indicated in my application above referred to, the kiln comprises three zones, namely, a pre-heating zone, a high-
10 temperature zone, and a cooling zone through which the trays pass from end to end, the temperature of the wares and trays thus being gradually raised in the pre-heating zone to a point where they will safely
15 withstand the highest temperature available, whereupon they pass into the high-temperature zone; and from the latter to the cooling zone. Both walls of the high-temperature zone are provided throughout their length
20 with upwardly and inwardly inclined passages 15 directed substantially toward the longitudinal mid line of the tunnel dome or arch 16, which is here formed of material of the highest refractory nature; and
25 through these passages the gases or oil fuel and air premixed in substantially such relative proportions that there is enough air and practically no more than is required to completely burn the fuel is directed in blasts
30 which may easily be made to maintain the dome substantially white hot, in the event spark plug porcelains are being treated, or at a lesser temperature when such is desirable by reason of the nature of the ware, as
35 in the case of enameling or coating iron ware. This "flameless" combustion generates unusually high heat in an exceedingly small space and has substantially no coloring influence on the ware, although the
40 latter is fully exposed.

In one embodiment of the invention indicated in the above identified application, the wares are passed through the kiln on cars of a conventional type, which necessarily include, as a protection for the wheels and other metal work thereof, a large mass or body of refractory and insulating material which must be heated up and cooled down at each passage of the car through the kiln, thereby causing costly losses both in time and heat. In order to effect a saving in these particulars, I preferably construct the kiln in the general manner shown in the drawing, wherein 50 indicates suitable conveyor elements—as shown, rollers—constructed of refractory material such as silicon carbide alundum, zircon or the like upon which the thin refractory carriers or trays 51, also preferably of the same or similar material, are carried, it being understood that there are a series of such rollers spaced from each other longitudinally of the tunnel distances considerably less than the length of the carriers. The floor of the tunnel is built in close to the over-hanging sides

of the trays and between the lines of conveyor elements with fire brick and insulation brick or material 52—53, so that the heat which would pass into a car body of the conventional type is absorbed by the stationary 70 mass and made use of to heat up the thin oncoming refractory slab or tray. In this connection, it will be understood that the drop in temperature through the tray or carriers 50 is relatively small, the temperature immediately beneath the carrier being too high to permit the use of metal rollers in the high heat zone especially, although metal rollers or conveying mechanism could be employed in parts of the pre-heating and cooling zones. 75 In the construction shown the refractory rollers are of sufficient diameter to protect the shafts 54 on which they are secured, and the latter extend outside the furnace to lubricated bearings 55. By forming the carriers 80 or trays and the wheels with associated bearing and guiding surfaces 56—57 the former are guided properly from end to end of the kiln. Obviously, the rollers may either be of the driven or of the free running type, in 85 which latter case any suitable means for pushing or propelling the slabs may be provided. Again, while I have shown the refractory conveyor elements in the form of rollers, it is clear that heat insulating conveyors of different construction, such, for example, as the reciprocating or step-by-step type, might be used.

From the foregoing it will be understood that the wares in all cases travel through the 100 kiln continuously from end to end whether the movement be constant or step-by-step, and it is in this sense that the term "continuous" is employed in some of the claims.

I claim:

1. In a continuous kiln for burning ceramic wares, a thin highly refractory carrier forming the support for the wares, supporting means on which the carrier travels through the kiln, the space about said supporting means being filled in with heat insulating material to a level close up to the lower side of the carrier, said supporting means including a highly refractory element projecting through the floor of the 110 kiln on which the carrier directly rests and with reference to which said carrier is movable.

2. In a continuous kiln having a high-temperature zone, a thin slab-like carrier 120 of highly refractory material on which ceramic wares rest in open exposure to heat reflected downwardly from the dome of the kiln, means on which and in respect to which the carrier moves through the kiln, the space 125 beneath the carrier in the high-temperature zone being filled in with incombustible material faced with highly refractory material at a level immediately below that of the lower surface of the carrier throughout the larger 130

- portion of said surface, the means on which and in respect to which the carrier moves in said high-temperature zone including highly refractory elements projecting slightly above 5 the facing of refractory material and contacting with the carrier, and means, protected from heat by said filled in incombustible and highly refractory material, and immovable longitudinally of said kiln, for supporting said means on which and in respect to which the carrier moves through the kilns.
3. In a continuous kiln having a high-temperature zone, a wide thin carrier of highly refractory material movable through said zone, conveyor elements of highly refractory material spaced apart from one another transversely of the kiln and supporting the carrier, the space between said elements being filled in with heat insulating material substantially up to the level of the lower surface of the carrier, the upper portion of said
- filling material being of a highly refractory nature.
4. Means for moving a comparatively, 25 thin highly refractory carrier through the high-temperature zone of a continuous kiln, said means including a conveyor element, with respect to which said carrier is movable longitudinally of the kiln, of highly refractory material projecting through the floor of the kiln to contact with the carrier.
5. Means for moving a thin highly refractory carrier through the high-temperature zone of a continuous kiln, said means includ- 35 ing a conveyor element of highly refractory material projecting through the floor of the kiln to contact with the carrier and with reference to which said carrier travels longitudinally of the kiln, a bearing external 40 to the kiln, and a shaft carried in the bearing and supporting said element.

In testimony whereof I affix my signature.
TAIN G. McDUGAL.
